UNITED STATES PATENT OFFICE.

OTTO J. GROEHN, OF DETROIT, MICHIGAN, ASSIGNOR TO CLAYTON & LAMBERT MANUFACTURING COMPANY, OF DETROIT, MICHIGAN, A CORPORATION OF MICHIGAN.

FIRE-POT CONSTRUCTION.

Application filed November 30, 1921. Serial No. 518,881.

This invention relates to a fire pot construction and refers more particularly to fire pot constructions such as are adopted for plumbers' furnaces and other oil burning devices.

One of the main objects of the invention is to utilize the flame generated for heating purposes for also heating the generator that preheats or vaporizes the liquid fuel. Other objects of the invention are to so construct and arrange the generator that it will act as a part of the deflector to curve the flame upward; to so construct and arrange the parts that the advantages above mentioned are obtained without materially changing constructions now in use, and in general to provide a new and improved fire pot construction of the character above mentioned. The invention also resides in the novel arrangement of the ears or lugs forming both a bale or handle connection and a stop against which the handle abuts and in such further details of construction and arrangements and combinations of parts as will more fully hereinafter appear.

In the drawings:

Fig. 1 is a side elevational view partly in section through a plumber's furnace embodying my invention;

Fig. 2 is a top plan view partly in section of the construction shown in Fig. 1.

Figs. 3 and 4 are detail views of the handle ears, and

Figure 5 is a detail transverse sectional view of the U-shaped fuel conductor showing the deflector plate in position.

Describing in detail the construction shown in the drawings, A designates the tank of a plumber's furnace having the usual pump A' and supporting standard A² which carries the combustion chamber B, the burner C and drip cup C'. The combustion chamber is in the form of a fire pot which is open at its upper end and also has an opening at its forward end provided with a support D hinged at D' to lugs D² carried by the wall of the combustion chamber B. The support D is adapted to form a support for soldering irons and other instruments (not shown), the part of the instrument to be heated projecting into the combustion chamber, while the handle part is supported by the support D. Within this chamber B there is located a U-shaped fuel conductor member E which has a rearwardly extending

center portion F into which the vaporized fuel for the combustion is discharged through the nozzle G. At the point of this discharge the fuel is mixed with air and returns to the outer members E² of the combustion member E. The members E² form the burners at opposite sides of the combustion chamber.

Heretofore it has been customary in constructions of this kind to have the burning gases directed upwardly through holes in the top of the members E². In the present construction I provide the members E² with longitudinally extending slots H which open inwardly toward the combustion chamber and by means of a deflector plate I the combustion flame from one of the burners E² is turned upwardly as shown best in Figure 5. In place of making this deflector plate for both sides of the U-shaped member it is preferably extended upon one side only, as shown in Figure 5, the combustion flame from the burner E² on the other side of the combustion chamber being deflected upwardly by the generating chamber J. Thus it will be noted that the outer members E² of the U-shaped fuel conductor E form burners, the fuel mixture passing from nozzle G, thence through the center portion F to the slots H of the burners E². Within the members E² may be located a wire screen E³ or the like, adapted to assist in mixing the fuel and air conducted to the slots H. The fuel is fed upwardly to the generator chamber through the conduit K which at its upper end opens into a chamber K' where it is forced to travel to the end of the tube K² and back through the latter to the port K³. The latter is controlled by a needle valve L carried by the screw-threaded stem L' and operated by the usual handle L². When this valve is opened the fuel then passes through the conduit M to the discharge orifice G which is kept clean by means of a clean-out member N carried by the screw-threaded stem N' adjusted by the usual hand wheel N². It will be noticed that the tube K² is offset to lie against the wall O which is directly adjacent the slot H where the burning takes place. By this novel construction the flame which is used to heat the solder tank or other members set upon the furnace is also utilized to heat the generating chamber since the flame from the slot H will strike against the member J thus playing an

intense heat upon the generator member which in turn also acts as part of the deflector to deflect the flame upwardly. This novel arrangement not only gives a simple and compact arrangement but permits of a relatively small drip cup C for starting the burner and also materially increases the efficiency of the entire fire pot construction.

In addition to the features above mentioned the invention also resides in the novel construction of handle ears Q. These ears, as in Figs. 3 and 4, consist of a metal stamping R which is offset at R' and then again inwardly offset at R². The latter portion 15 carries a tongue or lip S which extends through a hole in the wall of the furnace chamber B and is then bent upwardly in assembling the parts. At its lower end the handle ear is provided with bearing portions 20 T and T' which are riveted or otherwise rigidly secured to the wall of the furnace chamber. The offset arrangement of the handle ears has a further advantage in that the portion R² forms a rigid reinforced stop 25 against which the lower part of the handle T abuts when the device is being carried.

What I claim as my invention is:

1. In a fire pot construction for plumbers' furnaces or the like, the combination with a 30 burner having flame discharging means, of a generator located adjacent to a portion of said flame discharging means and adapted to deflect a portion of the entire burner flame upwardly, and a plate cooperating 35 with other portions of the flame discharge means for deflecting other portions of the said entire flame.

2. In a fire pot construction for plumbers' furnaces or the like, the combination with 40 a combustion chamber, of a U-shaped fuel conductor forming burner elements positioned at opposite sides of the combustion chamber, a deflector for directing the flame from one of the burners to the combustion 45 chamber, and a generator for deflecting the flame from the other of said burners to the combustion chamber.

3. In a fire pot construction for plumbers' furnaces or the like, the combination with a 50 U-shaped fuel conductor forming longitudinally extending burner elements, of a deflector plate for deflecting the flame from one of the burners, and a generator for deflecting the flame from the other of said burners.

55 4. In a fire pot construction for plumbers' furnaces or the like, the combination with a combustion chamber, of a plurality of burners below the combustion chamber, a deflector for directing the flame from one 60 of the burners to the combustion chamber, and a generator for deflecting the flame from the other of said burners to the combustion chamber.

65 5. In a fire pot construction for plumbers' furnaces or the like, the combination with a

fuel discharge nozzle, of a U-shaped burner in front of said nozzle, said burner having a rearwardly extending center portion between the arms of the said U-shaped burner and in the same horizontal plane therewith and into which the fuel from the nozzle is discharged, one side of said U-shaped burner having a perforation therein, and a generator located in the aforesaid plane and adjacent to said perforation, and in communication with said nozzle.

6. In a device of the class described, the combination with a combustion chamber, of a fuel discharge nozzle, a U-shaped burner below the combustion chamber, and in communication with said nozzle, said burner having a rearwardly extending center portion between the arms of the U-shaped burner for receiving the fuel from said nozzle, and a generator disposed between the 80 arms of the U-shaped burner, one arm of said burner having an opening for directing the flame laterally against the said generator whereby the flame is deflected upwardly to the combustion chamber, said burner center portion and generator lying substantially in the same plane horizontally.

7. A fire pot construction for plumbers' furnaces or the like having a fuel supply tank and a combustion chamber above the supply tank in the form of a fire pot open at the upper end, a U-shaped fuel conductor forming burner elements positioned at opposite sides of the combustion chamber adjacent the bottom of the said fire pot and provided with flame openings, said U-shaped conductor having a rearwardly extending center portion between the burner elements and in communication therewith for supplying fuel thereto, a fuel discharge nozzle positioned at the rear of the said center portion for directing fuel thereto, a generator nested horizontally between one of said burner elements and the said center portion, and in communication with said fuel supply tank and said discharge nozzle, said generator adapted to be heated by the flame from the said flame opening of the said burner element lying adjacent to the generator.

8. In a fire pot construction for plumbers' furnaces or the like having a fuel supply tank and a combustion chamber above the supply tank in the form of a fire pot open at the upper end, a U-shaped fuel conductor forming burner elements positioned at opposite sides of the combustion chamber adjacent the bottom of the said fire pot and provided with flame openings, said U-shaped conductor having a rearwardly extending center portion between the burner elements and in communication therewith for supplying fuel thereto, a fuel discharge nozzle positioned at the rear of the said center portion for directing fuel thereto, a generator extending longitudinally adjacent one of said

burner elements and in communication with said fuel supply tank and said discharge nozzle, said generator being located substantially in the plane of the said burner elements

3 elements and adapted to be heated by a flame from the said burner element lying adjacent the generator.

9. In a fire pot construction for plumbers' furnaces or the like, having a fuel supply 10 tank and a combustion chamber above the supply tank in the form of a fire pot open at the upper end, a U-shaped fuel conductor forming burner elements positioned at opposite sides of the combustion chamber adjacent the bottom of the said fire pot and provided with flame openings, said U-shaped conductor having a rearwardly extending center portion between the burner elements

and in communication therewith for supplying fuel thereto, a fuel discharge nozzle positioned at the rear of the said center portion for directing fuel thereto, a generator extending longitudinally adjacent one of said burner elements and in communication with said fuel supply tank and said discharge 20 nozzle, said generator adapted to be heated by a flame from the said burner element lying adjacent the generator, the said point of inlet of the fuel from the supply to the said generator lying intermediate the length 25 of the generator and means for causing the fuel within the generator to travel longitudinally thereof in successive opposite directions in passing to the said nozzle.

In testimony whereof I affix my signature.

OTTO J. GROEHN.
